By Clarence O'Brien.

Attorney

UNITED STATES PATENT OFFICE.

SANFORD L. SMITH, OF ORANGE, MASSACHUSETTS.

INTERNAL-COMBUSTION ENGINE.

Application filed July 27, 1926. Serial No. 125,264.

This invention relates to an improved explosive engine of the class embodying a plurality of rotors simultaneously operated by an expansion of exploded gases.

5 Briefly, the invention comprises a casing provided with four separate explosive chambers in each of which is located a rotor, the rotor being in the form of a toothed gear and the teeth of the several gears being in 10 intermeshing relation at predetermined points, whereby all of the teeth are permitted to act as pistons extending into the intervening pockets or spaces between the teeth, which also act as gas receiving and 15 conducting cylinders.

The features and advantages accompanying the improved structure will become apparent from the following description and drawings.

20 In the drawings:—

Figure 1 is a top plan view of a structure constructed in accordance with the present invention.

Fig. 2 is a side view of the casing with 25 one of the half-sections removed to expose the internal construction.

Fig. 3 is an enlarged fragmentary view of a portion of one of the casing sections showing a spark plug associated therewith.

30 In the drawings, the reference character 1 designates the casing which is composed of a pair of duplicate half sections bolted or otherwise detachably fastened together. The inner opposed faces of these sections 35 are recessed to provide a plurality of communicating compartments for the rotary gears 2, 3, 4 and 5. All of the gears are keyed to shafts 6 and they rotate in the directions indicated by the arrows 7.

40 The gear teeth are represented by the reference characters 8 and the gas pockets by the numerals 9. The teeth are preferably of a configuration shown and have flat outer ends in fluid-tight rotary contact with 45 the peripheral portions of the chambers. Moreover, the side faces of the gears are in fluid-tight contact with the side walls of the chambers.

The remaining reference characters are 50 in the form of main letters and duplicate letters embodying distinguishing primes. The reference characters q and q' represent one pair of exhaust ports, the reference p and p' represent another pair of exhaust

ports. All of these ports are located adjacent the peripheral portions of the casing. Then there are two additional exhaust ports represented by the reference characters u and u' . Adjacent these exhaust ports are indicated intake ports a and a' . The spark 60 plug openings into which the spark plugs 10 are tapped are represented by the reference characters b and b' .

The reference characters d , c , e , f , g , h , i , j , k , l , m and n represent different positions 65 in which the gears are represented to explain the serial operation. The teeth d , o are shown approaching the intake ports a and a' , the teeth cooperating with the port a' being designated by d' , c' , and e' . In this initial position, these teeth cooperate to produce a suction which draws in the gas from the carburetor. The carburetor is connected with the port a and a' through the medium 70 of suitable pipes.

It will be seen that a in the second position spaces s and s' contain gas at atmospheric pressure by the spaces g and g' and h and h' contain gas which has been slightly compressed by the teeth i and i' .

In the spaces j and j' the gas has been isolated and is fully compressed and is about to pass under the spark plugs b and b' , where it is ignited. The gas in the spaces k and k' has been ignited and is exerting a pressure tending to force the teeth l and l' out of these spaces. The pressure in the spaces m and m' has been partially reduced, owing to the partial displacement of the teeth n and n' but pressure will still be exerted until a full displacement is accomplished. The spaces o and o' have been isolated, and the only pressure remaining is the normal pressure after a full displacement of a tooth, and this will be allowed to escape when the exhaust openings are reached. In the spaces r , r' , s , s' , burnt gases still remain, but simply at atmospheric pressure.

As each space reaches a position corresponding to that of the spaces t and t' , the burnt gases will be fully expelled by the teeth d and d' through the main exhaust openings u and u' . The ignition will consist in the source of supply of the battery, a vibrator coil and spark plug, no timing mechanism being necessary.

In the arrangement explained, it will be

noticed that the force acts directly against the center of the gears and therefore does not tend to turn the gears in either direction, but as it acts on a point above the horizontal axes A and B, it turns the gears in the directions indicated by the arrow.

The advantage of the improved engine is simplicity and inexpensiveness of construction, combined with concentration of power, 10 continuity of action, and new mode and principle of operation.

It is believed that by considering the description in connection with the drawings, persons familiar with inventions of this 15 class will be able to obtain a clear understanding of the invention. Therefore, a more lengthy description is thought unnecessary.

While the preferred embodiment of the 20 invention has been shown and described, it is to be understood that minor changes coming within the field of invention claimed may be resorted to if desired.

Having thus described my invention, what I claim as new is:—

In an engine structure of the class described, a casing provided with two pairs of rotor compartments, two sets of rotors in said compartments for rotation, each rotor comprising a gear, the teeth of which have 30 their outer ends flat for contact with the peripheral portion of the complementary compartment, the spaces between the teeth constituting gas receiving and conveying pockets, intake ports in the casing cooperating with the gears at a point where certain of the teeth are in intermeshing relation, ignition holes located in the casing at points where certain other of the sets of gears again come into mesh, and exhaust 35 ports in the casing at points where the teeth of the different gears are entirely disengaged.

In testimony whereof I affix my signature.

SANFORD L. SMITH.
